(57)

CLAIM

The ornamental design for a container stopper, as shown and described herein.

DESCRIPTION

FIG. 1 is a top front isometric view of a container stopper showing the claimed design;
FIG. 2 is a front view thereof;
FIG. 3 is a rear view thereof;
FIG. 4 is a left view thereof;
FIG. 5 is a right view thereof;
FIG. 6 is a top view thereof; and,
FIG. 7 is a bottom view thereof.

(Continued)

The broken lines are shown for the purpose of illustrating environmental subject matter of an exemplary container and form no part of the claimed design.
